UNITED STATES PATENT OFFICE

104,546

DESIGN FOR A BOTTLE

Donald G. Topping, Coral Gables, Fla., assignor
to Ronrico Corporation, Arecibo, Puerto Rico,
a corporation of Puerto Rico

Application February 12, 1936, Serial No. 61,123

Term of patent 14 years

To all whom it may concern:

Be it known that I, Donald G. Topping, a citizen of the United States, residing at Coral Gables, in the county of Dade and State of Florida, have invented a new, original, and ornamental Design for a Bottle, of which the following is a specification, reference being had to the accompanying drawing forming a part thereof, wherein:—

Figure 1 is a side elevation of the bottle showing my new design.

Figure 2 is an end elevation of the bottle.

Figure 3 is a longitudinal vertical section taken on the line 3—3 of Figure 1.

Figure 4 is a longitudinal vertical section taken on line 4—4 of Figure 2.

Figure 5 is a top plan view, and

Figure 6 is a bottom plan view.

The characteristic features of my design reside in a bottle of the flask type having broad front and rear faces and narrower side faces, said bottle being provided with relatively broad and rounded sloping shoulders and being thickened from the front to the rear faces adjacent the shoulder portion and tapering downwardly on said broader faces along convex lines, said lines converging at the bottom portion to give the bottle a pinched-in effect, each narrower face of the bottle tapering convexly at its upper portion and then converging downwardly and inwardly to the bottom of the bottle.

I claim:—

The ornamental design for a bottle, substantially as shown and described.

DONALD G. TOPPING.
